UNITED STATES PATENT OFFICE.

EMIL ERICKSSON, OF CHICAGO, ILLINOIS, ASSIGNOR TO WM. A. FIELD COMPANY, OF CHICAGO, ILLINOIS, A CORPORATION OF ILLINOIS.

MECHANISM FOR CORRECTING PRINTING PLATES.

Application filed December 12, 1923. Serial No. 680,188.

To all whom it may concern:

Be it known that I, EMIL ERICKSSON, a citizen of the United States, residing at Chicago, in the county of Cook and State of Illinois, have invented certain new and useful Improvements in Mechanism for Correcting Printing Plates, of which the following is a specification.

The machine of the present invention is 10 designed for the purpose of quickly and accurately correcting inequalities in the type surface of a printing plate prior to the setting up of the plate in a printing press. Inequalities in the level of the type surface are 15 usually present as a result of the warping of the metal or other causes, so that such a plate requires correction in order that it will register an even impression when used in printing presses. The means provided in the 20 present machine are designed to apply pressure to all portions of the rear surface of a type plate, thereby leveling out the type surface against the level bed of the machine and transferring the inequalities of the rear 25 surface, after which said rear surface may, if desired, be leveled off by planing or like process.

In the drawing:

Figure 1 is a top or plan view of the 30 present machine;

Fig. 2 is a side elevation of the same;

Fig. 3 is an enlarged sectional view of a 35 portion of the pressure cylinder illustrating the projecting pins which afford the acting surface of the cylinder; and

Fig. 4 is a similar view showing a modified form of the pins.

The machine comprises a fixed table 10 upon which is slidably mounted a bed-plate 11 provided along each edge with a rack 12, the two racks being in parallel relation. The 15 upper surface of the bed-plate is a true surface which, in the form shown, is a flat plane, although it might be of evenly curved 20 formation for the correction of plates designed for use on cylinder presses.

To each side of the table is secured an upright standard 13 which projects above the table and affords a mounting for a cylinder 25 14 provided at each end with a trunnion 15 carried by a journal block 16 working in a slot 17 in the adjacent standard. Each journal block bears upon a spring 18 which is socketed in the corresponding standard, and

the elevation of the cylinder is regulated at 55 each end by means of a set-screw 19 threaded through the top of the standard. The arrangement is one which maintains the surface of the cylinder in spaced relation to the surface of the bed plate to permit the printing plates to be mounted upon the bed plate and fed beneath the cylinder, and the latter may be adjusted, within limits, to provide for variations in the standard thickness of 60 different printing plates.

The cylinder is provided at each end with a gear 20 which meshes with the underlying rack, so that as the bed plate is moved back and forth along the table, positive rotation 70 will be imparted to the cylinder. The cylinder comprises at each end a head 21 which is keyed upon a shaft 22, which shaft terminates in the trunnion 15, and the cylinder heads are united by a cylinder base wall 23 of lesser radius of curvature than the 75 cylinder heads.

Surrounding the base wall 22 is a cylindrical outer wall 23, the surface of which lies flush with the outer edges of the cylinder heads and between the two walls, and resting upon the base wall is a cushion layer 24 formed of rubber or other like yieldable material. The outer wall is provided with a large number of closely spaced 80 bores 25 each of which affords a guide for a pin 26, the outer end of which normally protrudes above the outer wall of the cylinder and the inner end of which is furnished with an enlarged head 27 which bears 85 against the yieldable cushion, the heads being spaced from one another to afford displacement area for the rubber or other like material when the pins are forced inwardly 90 in varying degrees during the correction process.

In Fig. 4, the construction is in all respects similar save for the fact that the base wall 22 is provided with a plurality of guide apertures 28 in radial alignment with the bores 25, and in this case the pins 29 are extended by the provision of tail pieces 30 which enter the guide apertures 28, coiled springs 31 being interposed which bear 95 against the head flanges 32.

In operation a type plate 33 is laid tight 100 face down upon the bed plate 11, and the bed plate is then moved under the cylinder 105 which causes the protruding pins to bear

upon the rear surface of the type plate and impart compression thereto in such degree as may be required to flatten out any inequalities in the plane of the type surface, which inequalities are thus transferred to the rear surface of the plate, the protruding pins meanwhile yielding locally in varying degree to accommodate the inequalities thus transferred to the rear surface. As the pins yield, they compress the rubber at points in contact with the pin heads and at the same time permit the rubber or like material to bulge or protrude into the intervening spaces to accommodate the distortion, so that the 15 distortions are all accommodated locally which permits the correction to be effected without an imposition of extreme pressures which might tend to injure the type surface.

20 In the cylinder of Fig. 4, a similar result is obtained by providing each of the pins with its own individual spring so that the various pins will yield locally to the degree necessary to accommodate local conditions.

25 The machine as a whole is one which permits the plates to be rapidly fed through the machine from either direction and provides for the imposition of a rolling pressure which can be easily applied by hand operation rather than by the use of hydraulic 30 or other presses of a character heretofore used. The simplicity of the device is one which particularly fits it for use in small printing establishments or under conditions 35 where the use of more involved machinery would be undesirable.

I claim:

1. In mechanism for correcting printing plates, the combination of a bed plate and 40 a cylinder mounted to apply a rolling pressure between the bed plate and the cylinder, a plurality of contact members outwardly protruding from the cylinder, and yieldable means for maintaining the contact members 45 in normal protruding relation to the cylinder, substantially as described.

2. In mechanism for correcting printing plates, the combination of a bed plate and a cylinder mounted to apply a rolling pressure 50 between the bed plate and the cylinder, a plurality of contact members outwardly protruding from the cylinder, and a yieldable cushion bearing against the inner ends of the contact members and normally holding 55 the same in outwardly protruding position, substantially as described.

3. In mechanism for correcting printing plates, the combination of a bed plate and a cylinder mounted to apply a rolling pressure 60 between the bed plate and the cylinder, a plurality of contact members outwardly protruding from the cylinder, yieldable means for maintaining the contact members in normal protruding relation to the cylinder, and means for varying the spaced 65 relation

between the cylinder and the bed plate, substantially as described.

4. In mechanism for correcting printing plates, the combination of a bed plate and a cylinder mounted to apply a rolling pressure 70 between the bed plate and the cylinder, a plurality of contact members outwardly protruding from the cylinder, a yieldable cushion bearing against the inner ends of the contact members and normally holding the same in outwardly protruding position, and means for varying the spaced relation 75 between the cylinder and the bed plate, substantially as described.

5. In mechanism for correcting printing plates, the combination of a bed plate, a cylinder, entrained mechanism between the bed plate and the cylinder for imparting rotation to the cylinder by the relative movement of the bed plate and cylinder, and yieldably mounted contact members carried by the cylinder and outwardly protruding therefrom, substantially as described.

6. In mechanism for correcting printing plates, the combination of a bed plate, a cylinder, entrained mechanism between the bed plate and the cylinder for imparting rotation to the cylinder by the relative movement of the bed plate and cylinder, yieldably mounted contact members carried by the cylinder and outwardly protruding therefrom, and means for varying the spaced relation 95 between the cylinder and the bed plate, substantially as described.

7. In mechanism for correcting printing plates, the combination of a slidably mounted bed plate, a fixedly positioned rotatably mounted cylinder overlying the bed plate, and yieldably mounted contact members carried by the cylinder and normally protruding from the surface thereof, substantially as described.

8. In mechanism for correcting printing plates, the combination of a slidably mounted bed plate, a fixedly positioned rotatably mounted cylinder overlying the bed plate, yieldably mounted contact members carried by the cylinder and normally protruding from the surface thereof, and entrained power transmission mechanism between the cylinder and bed plate for positively rotating the cylinder by movements of the bed plate, substantially as described.

9. In mechanism for correcting printing plates, the combination of a slidably mounted bed plate, a fixedly positioned rotatably mounted cylinder overlying the bed plate, yieldably mounted contact members carried by the cylinder and normally protruding from the surface thereof, a rack on the bed plate, and an intermeshing gear on the cylinder for rotating the cylinder by movements of the bed plate, substantially as described.

10. In mechanism for correcting printing plates, the combination of a table, standards 130

upwardly extending from the table, a bed plate slidably mounted upon the table and in spaced relation to the surface of the cylinder, and a plurality of yieldably mounted 5 contact members outwardly protruding from the surface of the cylinder, substantially as described.

11. In mechanism for correcting printing plates, the combination of a table, standards 10 upwardly extending from the table, a bed plate slidably mounted upon the table and in spaced relation to the surface of the cylinder, a plurality of pins entered through the outer surface of the cylinder and nor- 15 mally protruding therefrom, and yieldable means for normally maintaining said pins

in protruding relation, substantially as de- scribed.

12. In mechanism for correcting printing plates, the combination of a table, standards 20 upwardly extending from the table, a bed plate slidably mounted upon the table and in spaced relation to the surface of the cylinder, a plurality of pins entered through the outer surface of the cylinder and nor- 25 mally protruding therefrom, and a yieldable cushion carried by the cylinder and underlying the inner ends of said pins and normally maintaining the same in protrud- ing relation, substantially as described.

EMIL ERICKSSON.
